United States Patent Office

Des. 232,193

Patented July 23, 1974

232,193

COVER FOR A DATA TYPING MACHINE OR THE LIKE

Allen D. Alexander, Columbus, Ohio, assignor to
Industrial Nucleonics Corporation

Filed May 11, 1972, Ser. No. 252,522

Term of patent 14 years

Int. Cl. D18—99

U.S. Cl. D64—11 R

FIG. 1

FIG. 2

FIG. 3

FIG. 1 is a perspective view of a cover for a data typing machine or the like showing my new design, including the front slide, top side and part of the left side thereof.

FIG. 2 is another perspective view showing the right side, top side and front side.

FIG. 3 is a further perspective view showing the back side, top side and right side.

I claim:

The ornamental design for a cover for a data typing machine or the like, substantially as shown and described.
